UNITED STATES PATENT OFFICE.

EDWIN S. DWELLY, OF EAST ORANGE, NEW JERSEY, ASSIGNOR TO AMERICAN PIANO COMPANY, OF NEW YORK, N. Y., A CORPORATION OF NEW JERSEY.

MUSIC-ROLL SEAL.

1,426,161.

Specification of Letters Patent. Patented Aug. 15, 1922.

Application filed July 1, 1921. Serial No. 481,922.

To all whom it may concern:

Be it known that I, EDWIN S. DWELLY, a citizen of the United States, and a resident of the city of East Orange, in the county of 5 Essex and State of New Jersey, have invented an Improvement in Music-Roll Seals, of which the following is a specification.

The present invention relates to labels 10 for music rolls and the like.

The object of the invention is to provide a label which will securely hold a music sheet tightly rolled in that condition in which it leaves the manufacturer, while at 15 the same time provision is made for quick and easy opening of the roll when desired.

In music sheets commonly on the market, there is on each end a relatively stiff reinforcement having a central projecting tab 20 which is adapted to be connected to a hook carried by the roll at the center thereof. The reinforcement extends laterally of the central tab a substantial distance and affords a relatively stiff edge. The invention 25 takes advantage of this feature and provides a label such that the tab may be pulled to cause this reinforcement to sever the label transversely to release the music sheet.

30 It is a feature of the invention that the label is easily broken by the purchaser to open the roll by the simple action of pulling on the tab on the outer end of the roll. It is also a feature of the invention that the 35 label is destroyed by the act of opening the roll. It cannot therefore be replaced to simulate an unopened roll nor applied to another roll.

The invention will be better understood 40 from a description and a selected illustrative embodiment thereof. For the purpose of such description, reference is to be had to the accompanying drawings forming a part hereof in which

45 Figure 1 is a front view of a roll with a label of the preferred form encircling the roll to prevent unrolling of the music sheet.

Fig. 2 is a similar view showing the label 50 partially severed by the act of pulling on the tab.

Fig. 3 shows the label itself.

The label provided by the invention secures the outer free end of the music sheet against unwinding and overlies the edge of 55 the reinforced end of the roll adjacent the

tab in such manner that a pulling on the tab and consequent bending outward of the reinforced portion causes a tearing of the label to sever the same.

The label 1 is shown applied to a music 60 roll 2 of usual type. The music sheet is reinforced at its end and the reinforcement 3 is formed to present a tab 4 which carries a ring 5 all as usual. The label encircles the roll and overlies the edge 6 of the reinforcement 3. As shown and preferably, the label is provided with a hole 7 through which the tab 4 projects. When it is desired to open the roll, the label which forms a seal is readily broken by pulling on the 65 tab. The edges of the reinforced portion are relatively stiff and sever the label by an action which is substantially the same as that of tearing paper against the edge of a ruler. This is indicated in Fig. 2 in 70 which the label is shown as partially severed. If, as in the example illustrated, the label is not glued to the sheet, it is free to fall clear of the roll when severed and leaves nothing adhering thereto to look 75 unsightly or to interfere in the use of the roll. In the label shown, the manner of severing the label is indicated by a suitably positioned legend "To break seal, pull here." The label is preferably provided with a 80 gummed end 7, (Fig. 3) to facilitate its application to the roll. Obviously, any desired trade-mark, instruction or advertising matter may be applied to the label. The label is preferably made of paper of quality 85 sufficiently strong to prevent accidental tearing in the usual handling of the rolls, but not strong enough to make difficult the tearing of the same in the way intended.

It will be obvious that the label shown is 90 illustrative and that variations may be made without departing from the principle of the invention, or sacrificing the principal features thereof.

I claim as my invention:

1. The combination with a music roll 100 having a reinforced end presenting a tab and a relatively stiff edge adjacent thereto, of a label overlying said edge adjacent said tab to hold said end in rolled relation and 105 adapted to be torn thereby when the tab is pulled outwardly.

2. The combination with a music roll 110 having a reinforced end presenting a tab and a relatively stiff edge adjacent thereto,

2
of a label encircling said roll to prevent unrolling thereof and overlying said edge, said label being entirely unattached to the roll, whereby when the tab is pulled outwardly, the label is torn against the stiff edge of the reinforced end and when severed falls free of the roll.

3. The combination with a music roll having a reinforced end presenting a tab 10 and a relatively stiff edge adjacent thereto, of a label overlying said reinforced end and having a hole through which said tab extends to hold said roll from unrolling whereby when the tab is pulled outwardly 15 the label is torn by the outwardly pulled stiff edge of the reinforced end.

4. The combination with a music roll having a reinforced end presenting a tab and a relatively stiff edge adjacent thereto,

of a label encircling said roll to prevent unrolling thereof, said label having a hole through which the tab extends, said label being entirely unattached to said roll, whereby when the tab is pulled outwardly, the label is torn against the stiff edge of the reinforced end and when severed falls free of the roll.

5. A label for music rolls adapted to encircle the roll to prevent unrolling thereof, consisting of a strip of paper having a gummed end and having a hole through which the tab of the music roll may extend to facilitate severing of the label by pulling of the tab.

In testimony whereof, I have signed my name to this specification this 28th day of June, 1921.

EDWIN S. DWELLY.
